TEMPERATURE RESPONSIVE CONTROL

Murray Gunar, Lakewood, N. J.

Application August 14, 1957, Serial No. 678,257

8 Claims. (Cl. 158—140)

(Granted under Title 35, U. S. Code (1952), sec. 266)

The invention described herein, if patented, may be manufactured and used by or for the Government for governmental purposes, without the payment to me of any royalty thereon.

This invention relates to a temperature responsive device for controlling the flow of fluid and more particularly to a temperature responsive safety shutoff device for a gaseous fuel burner.

A general object of this invention is the provision of a new and improved control automatically to shut off the flow of fuel to a burner in the event that combustion at the burner is interrupted, thereby preventing the release of highly flammable and poisonous gases to the surrounding atmosphere with the resulting elimination of potential explosions and health hazards due to inhalation of the deadly gases.

An important object of this invention is the provision of an automatic cutoff valve for a fuel conveying line which requires the continuous application of manual force to the valve by the user to maintain a flow of fluid in the line in the absence of a predetermined temperature so that the device is bound to fail safe.

Another object of this invention is to provide an automatic safety fuel cutoff valve which includes a relatively simple mechanical arrangement of parts and is therefore capable of economical manufacture and trouble-free operation.

A further object of this invention is to provide a temperature responsive control including a safety cutoff feature for use with any fluid fuel consuming device which generates a temperature differential in operation.

Other objects and advantages of the invention will be apparent during the course of the following description.

In the accompanying drawings, forming a part of this application, and in which like numerals are used to designate like parts throughout the same,

Figure 1 is a plan view of a temperature responsive control in accordance with the present invention associated with a source of fluid fuel under pressure and a fuel burner, the control being shown in the closed position.

Figure 2 is a central vertical longitudinal section along line 2—2 of Figure 1,

Figure 3 is a transverse vertical section taken along line 3—3 of Figure 1,

Figure 4 is a similar section taken along line 4—4 of Figure 1,

Figure 5 is a similar section taken along line 5—5 of Figure 1,

Figure 6 is a similar section taken along line 6—6 of Figure 1,

Figure 7 is a similar section taken along line 7—7 of Figure 1,

Figure 8 is an enlarged partial central vertical longitudinal section showing the position of the valve members during operation of the burner, and

Figure 9 is a partial central vertical section similar

2

to Figure 2 showing a modification of the invention in the closed position.

Referring more particularly to the drawings where for the purpose of illustration a preferred embodiment of the invention is shown in Figures 1 to 8, the numeral 10 designates an elongated tubular member which forms a housing for the improved control of the present invention and a fuel inlet passageway, one end of which is joined to or formed integral with a conventional fuel burner 11 of a type appropriate for the type of fuel being used. At or near the opposed end of the housing 10 a connection 12 is provided for joining same to any suitable source of fluid fuel under pressure. This source may include a valve 14 for regulating the fuel pressure 15 to be supplied to the temperature responsive control.

The end of the housing 10 remote from the burner is closed by a cap 15 which is provided with a centrally located aperture having a packing gland 16 secured therein for a purpose to be described. A member 17 of high thermal conductivity is mounted adjacent the junction of the burner 11 and housing 10 at a position to be directly subjected to the heat at the burner 11. This heat conductor has an end depending into the passageway formed by housing 10, and this depending end has an aperture 18 25 for a purpose to be later described.

A portion of the inner surface of the housing 10 is provided with fixed longitudinally extending ribs 19 thereon spaced around its circumference. The function of these ribs 19 will be later described.

30 Three generally disc shaped valve members closely conforming in shape to the passageway formed by the housing 10 are housed therein. The center valve member, 20 is fixed in position within the passageway in sealed relation thereto and is provided with two generally sector shaped apertures or ports 21 and 22 extending therethrough as shown in Figure 6. The opposed surfaces of the valve member 20 are preferably covered with a suitable material 23 to improve the sealing contact between the various valve members.

40 The valve member 24 best shown in Figure 5 is located on the upstream side of the fixed valve member and is provided with a single generally sector shaped aperture or port 25 therethrough which normally registers with aperture 21 in fixed valve member 20. As indicated in phantom in Figure 6, the location and size of the aperture 25 is such that it overlaps portions of apertures 21 and 22 in valve member 20 when the valve member 24 is at the mid-point in its rotation between its normal position at which the aperture 25 therein registers with aperture 21 in fixed valve member 20 and a starting position wherein aperture 25 registers with aperture 22 in the fixed valve member 20 so that communication through these apertures is never completely cut off as explained hereinafter.

55 Valve member 26 shown in Figure 7 is positioned on the burner or downstream side of the fixed valve member 20 and is provided with a single generally sector shaped aperture or port 27 therethrough which is held in registering alignment with aperture 22 in the fixed valve member 20.

60 Valve member 26 is also provided with a series of arcuate apertures or ports 28 therethrough which are adapted to be closed by fixed valve member 20. The peripheral edge of valve member 26 is provided with a plurality of axially extending grooves 29 which coact with the previously described longitudinally extending ribs 19 on the inner surface of the housing 10 to lock this valve member against angular movement without impeding axial sliding movement thereof so that the aperture 27 therein is maintained in registering alignment with aperture 22 in fixed valve member 20 at all times.

70 Valve member 24 is keyed to one end of a shaft 30

rotatably journaled in a support 31 shown in Figure 4 and the packing gland 16 in cap 15, in sealing relation with the latter through which it projects to the exterior as shown in Figure 2. This projecting end of the shaft 30 is provided with a suitable knob 32 for manually rotating the shaft in a manner and for a purpose to be described. The valve member 24 is slideable axially of the shaft 30 and is biased along this shaft into sealing engagement with the fixed valve member 20 by compression spring 33.

The shaft 30 is angularly biased to a normal position wherein the aperture 25 in valve member 24 is in registering alignment with the aperture 21 in the fixed valve member 20 by means of a crank arm comprising a disc 34 keyed on the shaft as shown in Figure 3 and a tension spring 35 having one end fixed to a pin in crank arm disc 34 and the other end fixed in a screw 36 threaded in the control body 10. The spring 35 is tensioned to exert a continuing force on the crank arm 34 to return the shaft 30 and valve member 24 to the normal position.

The valve member 26 is mounted on one end of a shaft 37 which is slidably supported in a support 38 and is connected at its opposite end to a bimetallic thermostatic element 39 of any suitable type. The other end of the thermostatic element is fixed in good thermal conducting relation to the member 17 by appropriate means, in this case a stub shaft 40. The stub shaft 40 is fixed in good thermal conducting relation in the aperture 18 of the aforementioned heat conducting member 17 which extends into the passageway defined by the housing 10 from above the burner surface as best shown in Figure 2.

The thermostatic element 39 may be of any suitable type that will quickly contract upon an increase in the temperature thereof in accordance with the generally known operation of bimetallic thermostatic elements with resulting sliding movement of the shaft 37 and valve member 26 away from fixed valve member 20 from the position shown in Figure 2 to the position shown in Figure 8. The thermostatic element is adjusted to maintain sliding valve member 26 in closing relation with aperture 21 in fixed valve member 20 under normal ambient temperatures. It should be apparent that various configurations of bimetallic thermostatic elements may be utilized to achieve the desired result as shown and described.

From the foregoing description, it will be seen that under normal nonoperating conditions shown in Figures 2 through 7 the aperture 25 in rotary valve member 24 is in registering alignment with the aperture 21 in fixed valve member 20 and the aperture 21 is closed by sliding valve member 26. Aperture 27 in sliding valve member 26 is in registering alignment with aperture 22 in fixed valve member 20, the aperture 22 being closed by rotary valve member 24 when the ports are in the position described. It will also be noted that the arcuate apertures 28 in sliding valve member 26 are closed by fixed valve member 20. This, therefore, is the closed or nonoperating position of the control in which the flow of fluid therethrough is entirely prevented.

In the operation of the control, the operator manually rotates valve member 24 by means of knob 32 in a clockwise direction to its starting position at which position the aperture 25 in this valve member is aligned with aperture 22 in fixed valve member 20 and aperture 27 in sliding valve member 26 thereby permitting the flow of fuel through the control to the burner 11 where it is ignited in a usual manner. Suitable indicia or stops (not shown) are provided on the knob 32 and cap 15 to enable the operator to locate this position in rotating the knob 32. The temperature increase due to combustion at the burner surface is conducted by the heat conducting member 17 to the temperature responsive element 39 which contracts under the influence of the temperature increase causing movement of the sliding valve member 26 away from fixed valve member 20 whereupon communication

is established between apertures 21 and 22 in fixed valve member 20 and the apertures in the sliding valve member 26 as shown by arrows in Figure 8. Due to the sensitivity of the heat conducting member 17 and the thermostatic element 39, this action occurs within a few seconds after ignition of the burner. After this brief time interval, the knob 32 may be released by the operator allowing the rotary valve member 24 to return to its normal position under the influence of the tension spring 35. In this position, communication is established through apertures 25 and 21 of valve members 24 and 20 respectively and thence through the various apertures in sliding valve member 26 to the burner 11. It should be noted that the size and shape of aperture 25 is such that the flow of fluid is not cut off during the movement of valve member 24 to normal position as previously explained.

In the event of accidental extinguishment of combustion at the burner from any cause, the resulting decrease in the temperature of the thermostatic element 39 will cause the valve element 26 to be returned to its nonoperating position closing the aperture 21 in fixed valve member 20 and thereby cutting off the flow of fuel through the control.

The flow of fuel may be normally shut off either by cutting off the supply of fuel to the control or by turning valve member 24 to a position where the aperture 25 therein is closed by fixed valve member 20 until the flame at the burner is extinguished and then allowing the valve member to return to its normal position under the influence of the spring 35.

A modification of the present invention is shown in Figure 9. In this embodiment the control housing 10' is substantially identical with the previously described housing 10. Two generally disc shaped valve members 41 and 42 are located in the passageway defined by this housing. Valve member 41 is provided with a generally sector shaped aperture or port 43 therethrough closed by the valve member 42 when the parts are in nonoperating position. Valve member 42 is provided with a generally sector shaped aperture or port 44 therethrough which is closed by valve member 41 when the parts are in nonoperating position. A plurality of grooves in the peripheral surface of valve member 42 coat with longitudinally extending ribs 45 on the inner surface of the passageway 10' to lock this valve member against rotation during sliding movement thereof to be described in a manner similar to the manner in which the valve 26 in the first embodiment is locked against rotation. At least one of the opposed surfaces of valve members 41 and 42 is preferably provided with a suitable covering material 46 to promote sealing contact between the valve members. In this embodiment, it is also necessary that at least one of the valve members, preferably valve member 41, be made to closely conform to the interior surface of the body 10' or that a sealing ring (not shown) be used to prevent leakage of fluid between this valve member and the housing 10'.

The valve member 41 is fixedly mounted on one end of a shaft 47 which is slidably supported in a support 48 and a packing gland 16' in a cap 15' closing the outer end of the body 10'. The shaft 47 has a knob 32' on its outer end in the same manner as in the previously described embodiment of the invention. Shaft 47 is arcuately biased to a predetermined position by torsion spring 49 having one end anchored in support 48 and the other end fixed to the valve member 41. The spring 49 also serves to bias the valve member 41 axially into sealing relation with valve member 42.

Valve member 42 is fixed to one end of an axially movable shaft 50 which is slidably supported in a fixed support 51 and projects toward the burner end of the housing. The opposite end of shaft 50 is fixed to a bimetallic thermostatic element 39' in the same manner as in the previously described embodiment.

In starting a burner with this embodiment of the in-

vention, the rotatable and axially slideable shaft 47 is either rotated by the application of manual force to the knob 32' until the aperture 43 in valve member 41 is in register with the aperture 44 in valve member 42 thus establishing communication through the valve members or the shaft 47 is drawn to the left as seen in Figure 9 thus also establishing communication through the apertures 43 and 44 in the valve members 41 and 42. In either event there will be a flow of fluid to the burner where it is lighted in the customary manner. Under the influence of the temperature increase due to combustion at the burner, the thermostatic element 39' will draw the valve member 42 away from valve member 41 thereby establishing communication through the apertures 43 and 44 irrespective of the position of valve member 41. The knob 32' may then be released and the flow of fluid through the control will continue so long as heat is supplied to the temperature responsive element 39' by combustion at the burner.

Upon release of the knob 32' valve member 41 returns to its normal position under the influence of spring 49. In the event that combustion at the burner surface is accidentally extinguished, the resultant temperature decrease in the thermostatic element 39' will cause the valve member 42 to be returned to its nonoperating position closing the apertures 43 and 44 in valve members 41 and 42 respectively and thus shutting off the flow of fluid to the burner.

The normal shutoff of flow through the control in this embodiment of the invention is accomplished by a separate shutoff (not shown) at the source of fluid as in the embodiment previously described.

It is thus seen that I have described a new and improved automatic temperature responsive control with particular application to fluid fuel burning equipment which will automatically cut off the flow of fuel to a burner should the flame be accidentally extinguished and which in the absence of a flame at the burner completely prevents the flow of fuel therethrough unless a continuous manual force is applied by the operator so that the control is bound to fail safe. The desirable safety features of a control of this nature should be readily apparent to one familiar with the inherent danger of using fluid fuels.

It is to be understood that the forms of the invention herewith shown and described are to be taken as preferred examples of same and that various changes in the shape, size and arrangement of parts may be resorted to without departing from the spirit of the invention or the scope of the subjoined claims.

I claim:

1. A temperature responsive control comprising means defining a passageway for fluid, relatively movable valve members in said passageway each having at least one port therein, and conjointly operable means to control relative movement of said valve members comprising means including a temperature responsive element to move one of said valve members relatively to the other in response to a predetermined increase in the temperature thereof to a normal operating position at which communication is established through said ports, means for biasing said valve members for relative movement to a nonoperating position closing communication through the ports therein if said temperature responsive element is below a predetermined temperature and manually operable means to move the other of said valve members relatively to said one member in opposition to said biasing means to a starting position at which communication is established through said ports regardless of the temperature of said temperature responsive element, said biasing means being continuously effective to restore said valve members to said nonoperating position upon release of said manual means to cut off communication through said ports unless the temperature of said temperature responsive element is high enough to render the same opera-

tive to move the said valve members relatively to operating position.

2. An automatic cutoff for a fluid fuel burner comprising means defining an inlet passageway to connect the burner to a source of fuel under pressure, relatively movable valve members in said passageway each having at least one port therein for the flow of fuel therethrough, a thermostatic element connected to one of said valve members for moving the said member in response to a predetermined temperature at said burner to a normal operating position at which communication is established through the ports in said valve members, a shaft connected to another of said valve members and including a part external to said passageway and means for moving said shaft and the valve member connected thereto in opposite directions including a spring and a manually operable member operatively connected to the external part of said shaft to move the valve member connected thereto to a starting position at which communication is established through said valve members regardless of the temperature at said burner, said spring continuously biasing said shaft and the valve member connected thereto to a nonoperating position closing communication through the valve member so that flow of fuel through said passageway will be cut off upon release of said manually operable member unless the temperature at said burner is high enough to cause said first-mentioned valve member to be moved to its operative position by said thermostatic element.

3. An automatic cutoff for a fluid fuel burner comprising means defining an inlet passageway to connect the burner to a source of fluid fuel under pressure, relatively movable first and second valve members in said passageway having normally communicating ports, said second valve member having a second port normally closed by said first valve member, a third valve member having a part for closing the first mentioned port in said second valve member and a port communicating with the second port in said second valve member, means for shifting said first valve member to bring the port therein into communication with the second port in said second valve member and through said port with the port in the third valve member so as to open a passage for fluid through said valve members and means including an element responsive to an increase in the temperature at said burner for shifting said third valve member to a position at which communication is established between the port therein and the first mentioned port in said second valve member so as to establish communication through said valve members when said first valve member is at its normal position.

4. A temperature responsive control comprising means defining a passageway for fluid, a movable first valve member in said passageway having an aperture therethrough, means biasing said first valve member to a predetermined normal position, a second valve member fixed in said passageway having an aperture therethrough communicating with the aperture in said first valve member when said first member is in normal position, said second valve member having a second aperture therethrough normally closed by said first valve member, a movable third valve member in said passageway having an aperture therethrough communicating with the normally closed aperture in said second valve member, means including a temperature responsive element for shifting the third valve member to a position at which communication is established between the aperture therein and at least the first mentioned aperture in said second valve member so as to establish communication through said valve members when said first valve member is at its normal position and manually operable means to move said first valve member in opposition to said biasing means to a position at which communication through at least one aperture of each of said valve members is established

irrespective of the action of said temperature responsive element.

5. A temperature responsive control comprising means defining a passageway for fluid, a movable first valve member in said passageway having a port therein, means biasing said member to a predetermined normal position, a movable second valve member normally closing the port in said first valve member and having a port therein normally closed by said first valve member, means responsive to a temperature increase and decrease for moving said second valve member respectively to and from a position where communication is established between said ports and manually operable means for moving said first valve member in opposition to said biasing means to a position where communication is established between said ports irrespective of the action of said temperature responsive means, said biasing means being continuously effective to return said valve member to normal position upon termination of the application of manual force.

6. An automatic cutoff for a fluid fuel burner comprising means defining an inlet passageway to connect the burner to a source of fluid fuel under pressure, a shaft rotatably and axially slidably mounted within said passageway, a first valve member mounted on said shaft and having a port therethrough, means external to said passageway for manually operating said shaft to shift said first valve member, means mounted on said shaft for axially and rotatably biasing the same and said first valve member to a predetermined normal position, a second valve member movably mounted in said passageway and having a port therethrough adapted to be brought into communication with the port in said first valve member upon predetermined movement of the latter out of its normal position or upon movement of said second valve member from a predetermined inoperative to a predetermined operative position, structure on each of said valve members to cooperate with the other in closing communication through said ports when said two valve members are respectively at the predetermined normal position and the predetermined inoperative position and means including an element responsive to an increase in the temperature at said burner for moving said second valve member from the said predetermined inoperative position to the said predetermined operative position.

7. An automatic cutoff for a fluid fuel burner comprising means defining an inlet passageway to connect the burner to a source of fluid fuel under pressure, a rotatable shaft mounted in said passageway, means for biasing said shaft for rotation to a predetermined normal position, a first valve member mounted to turn with said shaft and having a port therethrough, a second valve member fixedly mounted within said passageway having a port

therethrough communicating with the port in said first valve member when the latter is in normal position, said fixed valve member having a second port therethrough which is closed by said first valve member when the latter is in normal position, a movable third valve member for closing communication through the said first port in said fixed valve member and having at least one aperture therethrough communicating with the second port in said fixed valve member, manually operable means to rotate said shaft in opposition to said biasing means to a position to establish communication through the port in said first valve member and the second port in said fixed valve member, means including a temperature responsive element for moving said third valve member to and from a position wherein communication is established between the port therein and the first mentioned port in said fixed valve member and means for conducting heat from the burner surface to said temperature responsive element.

8. An automatic cutoff for a fluid fuel burner comprising means defining an inlet passageway to connect the burner to a source of fluid fuel under pressure, a rotatable shaft mounted in said passageway, means for biasing said shaft for rotation to a predetermined normal position, a first valve member mounted to turn with said shaft and having a port therethrough, a second valve member fixedly mounted within said passageway having a port therethrough communicating with the port in said first valve member when the latter is in normal position, said fixed valve member having a second port therethrough which is closed by said first valve member when the latter is in normal position, a movable third valve member for closing communication through the said first port in said fixed valve member and having at least one aperture therethrough communicating with the second port in said fixed valve member, manually operable means to rotate said shaft in opposition to said biasing means to a position to establish communication through the port in said first valve member and the second port in said fixed valve member and means including a temperature responsive element for moving said third valve member to and from a position wherein communication is established between the port therein and the first mentioned port in said fixed valve member, the port in said first valve member being dimensioned to overlap both ports in said fixed valve member at the mid-point of the movement of said first valve member between a position where the port therein registers with the said second port in said fixed valve member and its normal position.
